UNITED STATES PATENT OFFICE

158,239

CASING FOR MEASURING AND CONTROLLING INSTRUMENTS

Walter P. Wills, Philadelphia, Pa., assignor, by
mesne assignments, to Minneapolis-Honeywell
Regulator Company, Minneapolis, Minn., a cor-
poration of Delaware

Application May 31, 1947, Serial No. 139,386

Term of patent 14 years

(Cl. D52—1)

To all whom it may concern:

Be it known that I, Walter P. Wills, a citizen of the United States and resident of Philadelphia, in the county of Philadelphia and State of Pennsylvania, have invented a new, original, and ornamental Design for a Casing for Measuring and Controlling Instruments, of which the following is a specification, reference being had to the accompanying drawing, forming part thereof.

Fig. 1 is a front view of a casing for measuring and controlling instruments, showing my new design;

Fig. 2 shows a side elevation of the instrument casing;

Fig. 3 shows a bottom view of the instrument casing; and

Fig. 4 is a perspective view of merely the front panel portion of the device.

The dotted line showing in the drawing figures is for illustrative purposes only.

I claim:

The ornamental design for a casing for measuring and controlling instruments, substantially as shown and described.

WALTER P. WILLS.
